UNITED STATES PATENT OFFICE.

HERMAN B. FERGUSON, OF PITTSBURGH, PENNSYLVANIA.

APPARATUS FOR IRONING GARMENTS.

1,078,269.

Specification of Letters Patent. Patented Nov. 11, 1913.

Application filed March 14, 1913. Serial No. 754,275.

To all whom it may concern:

Be it known that I, HERMAN B. FERGUSON, a citizen of the United States, residing at Pittsburgh, in the county of Allegheny and State of Pennsylvania, have invented 5 certain new and useful Improvements in Apparatus for Ironing Garments, of which the following is a specification.

The invention relates to garment ironing 10 apparatus or machines designed to eliminate the hand ironing necessary in preparing manufactured garments such as shirts for sale. The invention has for its primary objects, the provision of a machine or apparatus 15 in which it is possible to iron or smooth the entire shirt at one operation; the provision of a machine permitting a convenient and effective straightening of the material of the garment preliminary to the 20 final pressing operation; and the provision of a machine which will properly iron or press the material of the garment at and adjacent the neck band. One embodiment of the invention is illustrated in the accompanying 25 drawings wherein—

Figure 1 is a perspective view of the apparatus employed, Fig. 2 is a face view of the upper presser member, Fig. 3 is a face view of the lower presser member, Figs. 4, 30 5, 6 and 7 are diagrammatic views illustrating the steps employed in preparing the shirt for the ironing or pressing operation, Fig. 8 is a view of the front of the shirt as finally folded, Fig. 9 is a plan view of the 35 shirt band supporter, Fig. 10 is a view of the shirt as folded with the neck band supporter in position, Fig. 11 is a diagrammatic side elevation view showing the relative position of the presser plates with the shirt to be 40 pressed therebetween, just before the pressing operation occurs, Fig. 12 is a view similar to that of Fig. 11, but with the presser plates in their first operative position, at which time one end of the shirt is gripped 45 between the plates while the other end is left free to be straightened before the final pressing operation, Fig. 13 is a view similar to that of Figs. 11 and 12 but with the presser plates in their final pressing position, Fig. 50 14 is a view illustrating the presser plates and shirt after the pressing operation has been completed and the presser plates separated to permit of the removal of the shirt, Fig. 15 is an enlarged detail of one of the 55 yokes, and Fig. 16 is an elevation of a modification.

Referring to Fig. 1 of the drawing, 1 is the framework or pedestal of the machine securely mounted upon the base plate 2 and preferably formed of metal. The end of the framework 1 carries the hollow metal presser plate 3 provided at one end with a recess 4 for the reception of the neck band of the shirt. Steam is provided for heating the plate 3, by means of the pipe 5, while another pipe 6 serves to take care of the condensation in this plate. 60 7 is the lower presser plate or member, such plate also being hollow and heated by means of steam from the pipe 8 (Fig. 3) such pipe having a flexible portion 9 as indicated in Fig. 1, to permit of the movement of the plate 7. The condensation from the plate 7 is taken care of by means of the pipe 10 (Fig. 3). 65

The plate 7 is provided at one end with 70 a pair of arms 11 straddling the brackets 12 and 13. The brackets are slotted as indicated at 14, and in these slots works a transverse rod 15 secured to the arms 11. The front end of the plate 7 is thus guided vertically and held against lateral or twisting movement. The front and rear ends of the plate 7 at the lower side thereof are provided with the pivoted yokes 16 and 17 provided with the downwardly projecting 75 bosses 18 and 19. The bosses 18 and 19 have telescopic relation with the rods 20 and 21 therebeneath, by means of the construction shown in detail in Fig. 15. By reference to this figure it will be seen that the boss 18 80 slidingly receives the upper end of the rod 20, a strong spring 22 being interposed between collars carried by the boss 18 and rod 20. This arrangement provides for the yielding application of power to the plate 85 7. The connection between the boss 19 and rod 21 is similar to the one just described, a spring 23 providing for the yielding application of force to the right hand end of the plate 7. 90

The two rods 20 and 21 are operated by means of the foot treadles 24 and 25 pivoted to the base plate 2 and having their left hand ends connected to the rods 26 and 27 in the manner illustrated. The opposing 105 ends of the rods 20 and 26 and 21 and 27 are threaded right and left hand and carry the adjusting nuts 28 and 29, such nuts serving to adjust the position of the plate 7.

In operating the machine a fully folded 110 shirt such as that shown in Fig. 8 is placed upon the plate 7, with the neck band in

position to fit inside the recess 4 in the upper plate 3. The parts then occupy the position illustrated in Fig. 11. The lever 24 is then forced down by the foot, causing the front end of the plate 7 to rise and grip the shirt against the end of the plate 3. The operator then grasps the right hand end of the shirt and pulls it perfectly straight and smooth (Fig. 12). As soon as this is accomplished the lever 25 is operated to cause the rear end of the plate 7 to move up, the parts at such time occupying the position indicated in Fig. 13. The shirt is held in this position a sufficient length of time to secure the necessary ironing or pressing action, at which time the ends of the levers 24 and 25 are released and the plate 7 moved down by gravity to the position indicated in Fig. 14, at which time the shirt may be removed and another one placed in position.

In order to hold the neck band of the shirt in vertical position during the pressing operation and secure its contact with the surface of the plate 3 in the recess 4, the supporting member 30 illustrated in Fig. 9 is preferably employed. This member is made of spring metal with overlapping ends guided upon each other by means of a pin 31 carried by one end of the strip of metal 30 working in the slot carried by the other end, this being a well known construction in the art. This supporter fits in the neck band, and by reason of the yielding character of the metal will fit neck bands of different sizes and hold them in upright position during the pressing operation.

In order to insure a complete pressing, and add to the efficiency of the apparatus, a presser board 32 of metal or any other desired material, may be used as indicated in Fig. 4. The shirt is folded over this board as indicated diagrammatically in Figs. 4, 5, 6, and 7, and is left in position inside the shirt during the pressing operation, after which it is removed by sliding it endwise without unfolding the shirt. By reference to Figs. 4, 5, 6, and 7, it will be seen that the back of the shirt and the front portion or bosom thereof lie to the front of the board 32, while the arms, the side portions of the shirt, and the lower portion of the shirt lie to the rear of such board, this being the usual method employed in folding shirts. The board 32 not only serves to more effectively secure a proper ironing or pressing of the shirt, but gives a form about which the shirt may be folded. In some classes of work it may be found desirable to omit the use of this presser board, and in some cases the shirt may be folded over card board, which may or may not be left in position during the pressing operation, depending upon the character of the material.

Fig. 16 illustrates in side elevation a modi-

fied type of construction, which is in some respects preferred, particularly in that only a single operating treadle need be used, instead of the two treadles of the structure of Fig. 1. In this structure 1' is the framework of the machine, and 2' is the base plate. The framework 1' carries an upper hollow presser plate 3' having the steam supply and drainage pipes 5' and 6', as in the other type of construction. The lower plate 7' is also hollow and provided with the pipe 8' and 10'. An operating rod 34 is slidably mounted in the guide 35, and is actuated from the treadle lever 36, such lever being connected to the lower end of the rod 34 by means of the link 37. The presser plate 7' is pivotally supported as indicated at 38, and a spring 39 provides for the yielding application of power from the rod 34 to the plate 7', the construction at this point being the same as that heretofore described for the machine of Fig. 1, and as illustrated in Fig. 15. A lever 40 serves to maintain the plate 7' inclined during the first operation of the treadle 36. The lever is provided with a handle and with a notch fitting over a pin 41 carried by the rod 34. A plate 42 is slidably mounted on the top of the plate 7', so that the plate can be pulled forward from beneath the plate 3' and the shirt applied thereto, after which the plate can be returned to the position illustrated.

In operation, after the shirt has been applied to the plate 42 and moved to the position illustrated in Fig. 16, the treadle is operated to cause the right hand end of the plate 42 to move up and press the front end of the shirt against the plate 3'. After the shirt has been smoothed out upon the plate 42 the lever 40 is released from its pin 41, power being at the same time applied to the treadle 36 to still further actuate the rod 34 and the plate carried thereby. This last actuation of the treadle causes the plate 42 to move up to complete pressing position. The end of the presser plate 7' is enlarged and given additional weight as indicated at 43, in order to cause the plate to automatically assume the inclined position shown, after the release of the treadle, and the upper plate 3' is recessed at the neck band the same as in the construction of Figs. 1 and 2.

The process and apparatus as heretofore described permits of the pressing or ironing of shirts with great rapidity, and the garment after being ironed is found to be substantially as well done as in the processes now in vogue wherein much hand labor is necessary, and wherein only one fold of the material can be pressed at a time. The use of the neck band supporter as shown in Fig. 10 when taken in connection with the recessed upper plate 3 secures a proper ironing or pressing of such band and the

material of the shirt immediately surrounding the neck band, thus eliminating the hand labor at this portion of the garment. The shirts may be ironed damp or dry, and both of the plates 3 and 7 may be heated; or only one of such plates, depending upon conditions. In some cases it may be desirable to use a layer of cloth or a pad between the surface of the plate and the garment being ironed. Any desired type of power operating means for the rods 20 and 21 may of course be substituted for that illustrated, and the plate 7 may be otherwise guided in its movements, the only requirement being that the plate be made to approach at one end first in order to grip the shirt, leaving the other portion of the shirt free so that it may be straightened preliminary to the final movement of approach between the plates. Various other means for heating the plates might also be employed, the drawings illustrating only one embodiment of a large number of means by which the invention might be carried out. In those cases in which the apparatus is to be used with starched shirts, the presser board 32 is inserted between the shirt front and the back of the shirt, and the garment is pressed without folding the other portions of the shirt.

What I claim is:

1. Apparatus for ironing garments comprising a fixed plate, a movable plate mounted for movement toward and from the fixed plate and for oscillation about a point adjacent one end, means for heating one of the plates, means for moving the end of the oscillatory plate toward the fixed plate to grip the end of the garment leaving the other end of such plate separated from the fixed plate, and means for moving such other end toward the fixed plate while maintaining the first mentioned end of the oscillatory plate in gripping position.
2. Apparatus for ironing garments, comprising lower and upper flat presser plates,

means for heating one of the plates, and means whereby one of the plates is caused to move toward the other at one end and at an angle to the other plate, to grip the end of the garment to permit it to be pulled straight, the ends of the plates opposite to the gripping ends being left separated to permit such straightening operation preliminary to the final pressing operation. 55

3. Apparatus for ironing garments, comprising a lower presser plate and upper plate, means for heating one plate, and mechanism for causing one of the plates to approach the other in two movements, the first movement bringing two opposing ends of the plates into gripping engagement with the end of the garment while the other ends of the plates are left separated to permit the garment to be pulled straight, and the second movement bringing the separated ends of the plates into pressing engagement with the garment, while the first mentioned ends are maintained in gripping engagement with the garment. 70

4. Apparatus for ironing garments, comprising a pair of relatively movable opposing presser plates mounted to permit first a relative movement of approach with one plate inclined toward the other so that the garment is first gripped at one end between the ends of the plates and second a movement bringing the plates into substantial parallelism and close together to press the entire garment, and operating devices giving the said relative movements and maintaining the gripping ends of the plates in gripping position while the plates are being brought into substantial parallelism. 80

In testimony whereof I have hereunto signed my name in the presence of the two subscribed witnesses.
